CLAIM

We claim the ornamental design for a cord box, as shown and described.

DESCRIPTION

FIG. 1 is a front perspective view of a cord box showing our new design in an open configuration of use;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and

FIG. 7 is a bottom plan view thereof.

FIG. 8 is a front perspective view of the cord box of FIG. 1 in a closed condition;

FIG. 9 is a front perspective view of embodiment two of the cord box showing our new design in an open configuration of use;

FIG. 12 is a front elevational view thereof;

FIG. 11 is a left side elevational view thereof;

FIG. 12 is a right side elevational view thereof;

FIG. 13 is a rear elevational view thereof;

FIG. 14 is a top plan view thereof; and

FIG. 15 is a bottom plan view thereof; and,

FIG. 16 is a front perspective view of the cord box of FIG. 9 in a closed condition.

The broken lines in the cord box are not part of the claimed design.

1 Claim, 10 Drawing Sheets
